UNITED STATES PATENT OFFICE.

GRACE O. FURROW, OF HOOD RIVER, OREGON.

ADJUSTABLE MUSIC-DESK FOR PIANOFORTES.

1,037,233.

Specification of Letters Patent.

Patented Sept. 3, 1912.

Application filed November 17, 1911. Serial No. 660,917.

To all whom it may concern:

Be it known that I, GRACE O. FURROW, a citizen of the United States, residing at Hood River, in the county of Hood River 5 and State of Oregon, have invented a new and useful Adjustable Music-Desk for Pianofortes, of which the following is a specification.

My invention is an attachment for the 10 pianoforte, and adjustable music desk, for the use of children who study the pianoforte, and for teachers who teach pianoforte to children, and the objects of my invention are first, to allow a child's music to 15 be placed in a position that will accommodate his eyes, thus preventing them from strain and other injury; second, to allow a child's music to be placed properly before him, which will admit to him opportunity 20 for proper advancement in his study of music. I attain these objects by use of proper materials for the desk and mechanism illustrated in the accompanying drawing.

25 The adjustable music desk is to be manufactured of celluloid colored to represent mahogany, walnut, oak, ebony, rosewood, teak, Circassian walnut, burl walnut, mission finish or other woods or finishes or 30 representatives of same. Transparent celluloid may be used, also wood, metal, or any material or combination of material desirable.

In the drawing—Figure 1 is the front 35 view of the desk. Fig. 2, views of adjuster; Fig. 3, views of supporting bracket which attaches desk to grand pianoforte desk and panel desk of upright pianoforte. Fig. 4, views of supporting bracket which attaches 40 desk to desk of upright pianoforte with full duet swinging music desk. Fig. 5, desk attached to panel desk; Fig. 6, desk attached to full duet swinging music desk. Fig. 7 a side view of desk, adjuster, and supporting 45 bracket used to attach desk to panel desk of pianoforte.

Similar letters refer to similar parts throughout the several views.

The desk is composed of three panels A, 50 B, and M of which the lower portions form the music holder. The groove 'n' of center

panel admits tongues 'c', 'c' of side panels and the dovetailed groove 'n' in the upper portion of panel M admits correspondingly shaped ribs on upper portions of the panels 55 A and B. By means of this construction the desk is adjustable in width. This adjustment may be omitted for pianoforte with full duet swinging music desk.

The side panels are provided with a series 60 of key hole openings 'd' for reception of lugs 'e' on the adjuster by means of which the desk is adjustable in height. The adjuster is provided with a flat portion carrying the lugs 'e' and a semi elliptical portion 65 for contact with the desk. The latter is provided with a series of marginal openings 'o' for reception of a lug on the supporting bracket 'i'. By means of these openings the desk may be adjusted angularly.

70 Fig. 3 shows supporting bracket used with grand pianoforte desk. Bracket 'i' may vary in width to fit different makes of pianoforte. 's' attaches the desk to back of pianoforte desk.

75 In Fig. 4 'l' and 'k' are a solid cylinder and 'k' may vary in length to fit different makes of pianoforte. 't' attaches desk to back of pianoforte desk.

I am aware that prior to my invention, 80 book and music holders have been made, base or bracket supported, which are adjustable in width, and others base supported, adjustable vertically but

I claim—

An adjustable music holder comprising central and side panels, the latter being adjustable on the central panel by means of tongue and groove connections, a vertical series of key hole openings in the side 90 panels, an adjuster semi-elliptical in outline with flat portion provided with lugs adapted to enter the openings in side panels, a series of marginal openings in the adjuster, and a supporting bracket having a 95 lug adapted to enter said openings and securing the holder to a support substantially as described.

GRACE O. FURROW.
